UNITED STATES PATENT OFFICE.

LEWIS H. HANEY, OF LOS ANGELES, CALIFORNIA, ASSIGNOR TO STANDARD DEEP WELL COMPANY, OF LOS ANGELES, CALIFORNIA, A CORPORATION OF CALIFORNIA.

PUMP.

Application filed June 20, 1921. Serial No. 478,990.

To all whom it may concern:

Be it known that I, LEWIS H. HANEY, a citizen of the United States, residing at Los Angeles, in the county of Los Angeles and 5 State of California, have invented new and useful Improvements in Pumps, of which the following is a specification.

This invention is a pump adapted for deep well pumping and including a casing sunk 10 into the well and provided with a foot valve at the lower end of the same. A rotatable rod extends through the casing and is provided with impellers at spaced points for raising a column of liquid through the casing. 15

In order that the impellers, by their presence in the casing, will not decrease the cross sectional area of the casing which is open to the flow of the liquid, said casing 20 at the impellers is increased in diameter, and as a consequence an equal volume of liquid may flow throughout the length of the casing in order to prevent back pressure.

The invention also contemplates the provision of means within the well casing for preventing whirling of the column of liquid due to the action of the impellers, and as a result the loss of head in the column of liquid is prevented.

30 The invention will be readily understood from the following description of the accompanying drawings, in which:

Figure 1 is a vertical section through a well showing a pump constructed in accordance with the invention, in side elevation.

Fig. 2 is a detail section on the line 2—2 of Fig. 1.

In the drawings I have shown a deep 40 wheel bore at 1, and said bore receives the well casing 2 which at its lower end is provided with an inlet check valve 3. Rod 4 rotates within casing 2 and has impellers 5 fixed thereon so as to be rotated with the rod 45 within the casing for elevating a column of liquid.

The impellers 5 are so positioned upon rod 4 as to be opposite joints between sections of the casing 2, and the couplings for said 50 casing sections are so arranged as to enlarge the cross sectional diameter of the well casing and thereby permit a uniform flow of liquid through the casing irrespective of the space taken up by the impellers.

55 As an instance of this arrangement, the

ends of adjacent sections of casing 2 are spaced from one another with impeller 5 positioned in said space, and coupling sleeves 6 and 7 are threaded onto the ends of the respective casing sections. These coupling sleeves divergently taper away from their ends which are threaded onto casing sections, and the adjacent ends of said coupling sleeves are threaded as shown at 8 in order that they may be connected to form the 60 coupling for the sections of the casing. 65

In practice, the coupling sleeve 6 is preferably elongated and is adapted to receive impellers 5 within the enlarged end of the casing, while coupling sleeves 7 is relatively 70 short so as to be connected to coupling sleeve 6 below impeller 5.

In order to prevent whirling of the column of liquid in the well casing, vanes 10 are radially disposed in the casing and are preferably carried by coupling sleeves 7. These vanes are radially disposed and form a bearing 11 for rod 4. 75

It will be noted that my improved construction contemplates the use of a practically continuous impeller shaft throughout the entire length of the pump or well tube and said shaft being accurately balanced, which permits operation at the lowest possible speed for the maintenance of efficiency; 80 and, in this connection it will be understood that slow speeds of operation eliminate vibration and also the possibility of crystallization, and likewise eliminate overheating of the bearings in the pump head. 85

The provision of an inlet check valve at the bottom of the pump prevents water from escaping downwardly through the bottom of the well tube, maintains a water column within the well tube when the pump stops, 90 thereby excluding air and preventing deterioration of parts, and provides for atmospheric pressure on suction when the water drops below the lower pump runner or impeller. 95

The enlargement of the well tube adjacent to the impellers permits the latter to be constructed with ample blade surface so as to render the action of lifting the water comparatively easy, permits the installation of guide vanes in the well tube without materially obstructing the flow of water, maintains practically the same area throughout the length of the well tube, and permits the water to pass through the runners at the 100 105 110

same velocity as through the well tube sections that connect the enlarged portions. Further, the enlargements in the well tubing permits the impellers to be made larger than the tubing and in the proper proportions for the imposed duties.

It will be readily understood that minor changes in the size, form and construction of the various parts of my improved pump may 10 be made and substituted for those herein shown and described without departing from the spirit of my invention, the scope of which is set forth in the appended claims.

Various changes may be made without departing from the spirit of the invention as 15 claimed.

What is claimed is:

1. A pump comprising a casing formed of 20 sections, a pair of coupling sleeves connecting the confronting ends of adjacent sections, one of said sleeves exceeding in diameter that of the sections and tapered in one direction from a point substantially medially of its ends, the other sleeve being

relatively short and tapered from the first 25 sleeve to the adjacent section, a plurality of vanes disposed radially within and formed integrally with the short sleeve, a bearing sustained axially within the sleeve by said vanes, a shaft journaled in the bearing, and 30 an impeller fixed to the shaft and disposed within the first sleeve.

2. A pump comprising a casing formed of sections, a pair of coupling sleeves connecting the confronting ends of adjacent 35 sections, one of said sleeves being relatively long and the other relatively short, with the former arranged above the latter, a plurality of vanes disposed radially within the short sleeve, a bearing sustained axially 40 within the sleeve by said vanes, a shaft journaled in the bearing, and an impeller fixed to the shaft above the vanes and within the long sleeve.

In testimony whereof I have signed my 45 name to this specification.

LEWIS H. HANEY.
